(57) **CLAIM**

The ornamental design for a floor pad, as shown and described.

DESCRIPTION

FIG. 1 is an orthogonal view showing the new design for a floor pad.

FIG. 2 is a top view thereof;

FIG. 3 is a bottom view thereof; and,

FIG. 4 is a right side profile view thereof; the left side view, front side view and back side view thereof being the same. The dark stippling represents an abrasive texture. The abrasive texture sits on generally flat surfaces of the pad.
